UNITED STATES PATENT OFFICE.

HENRY G. FECHTEL AND GEORGE H. FECHTEL, OF ST. LOUIS, MISSOURI.

DESIGN FOR A BODY FOR VELOCIPEDe-WAGONS.

SPECIFICATION forming part of Design No. 29,578, dated November 1, 1898.

Application filed September 14, 1898. Serial No. 690,983. Term of patent 14 years.

To all whom it may concern:

Be it known that we, HENRY G. FECHTEL and GEORGE H. FECHTEL, of the city of St. Louis, State of Missouri, have invented and 5 produced a new and original Design for Bodies for Velocipede-Wagons, of which the following is a full, clear, and exact description, reference being had to the accompanying drawings, forming a part hereof.

10 Figure 1 is a side elevation of a body for velocipede-wagons embodying our new design. Fig. 2 is a plan view thereof.

15 As shown in the drawings, the leading or material feature of our design consists of a rectangular body 1, from the under forward side of which extend forwardly and upwardly the compound curved frames 2, the same being united at a point some distance in front

of the body 1, and immediately in front of the point where said frames unite is the bifurcated head 3. Extending rearwardly a short distance from where the two frames unite is a short arm 4, which terminates in a horizontally-arranged rectangular head 5.

We claim—

25 The design for a body for velocipede-wagons, substantially as herein shown and described.

In testimony whereof we affix our signatures in presence of two witnesses.

HENRY G. FECHTEL.
GEORGE H. FECHTEL.

Witnesses:

C. W. BLOCK,
JNO. C. HIGDON.
